UNITED STATES PATENT OFFICE.

RALPH J. TEETOR, OF INDIANAPOLIS, INDIANA, ASSIGNOR TO LINK-BELT COMPANY, OF CHICAGO, ILLINOIS, A CORPORATION OF ILLINOIS.

COAL-CUTTING CHAIN.

1,181,185.

Specification of Letters Patent. Patented May 2, 1916.

Application filed March 19, 1915. Serial No. 15,659

To all whom it may concern:

Be it known that I, RALPH J. TEETOR, a citizen of the United States, residing at Indianapolis, in the county of Marion and State of Indiana, have invented a certain new and useful Improvement in Coal-Cutting Chains, of which the following is a specification.

My invention relates to improvements in coal cutting chains.

It refers most specifically to the cutting portion of the chain.

One object of my invention is to provide a chain which will be more durable and easily adjusted and which will cut in a more satisfactory manner.

Other objects will appear from time to time in the specification.

It is illustrated more or less diagrammatically in the accompanying drawings, wherein—

Figure 1 is a diagrammatic view of a coal cutting machine for the purpose of illustrating the operating of the chain; Fig. 2 is a plan view of the chain itself on an enlarged scale; Fig. 3 is a section on the line 3—3 of Fig. 1 on an enlarged scale; Fig. 4 is a side elevation of the chain; Fig. 5 is a median section through the central cutter and link shown in Fig. 4; Fig. 6 is a section on the line 6—6 of Fig. 5; Fig. 7 is a plan view; Fig. 8 a side elevation and Fig. 9 an end elevation respectively of the link shown at the extreme right-hand end of Fig. 4.

Like parts are indicated by like letters throughout the several figures.

In order to make clear the purpose and operation of my invention, I have illustrated the chain diagrammatically in its relation with the coal cutting machine.

1 is a rectangular supporting frame. It carries at one end the housing 2 in which is located any suitable motor and driving mechanism.

3 is an A-frame suspended on the frame 1. This A-frame has its apex immediately beneath the motor so that the drive wheel not here shown which drives the chain may be located at the apex of the A frame. At the two other corners of this frame are located the sprockets 4 and 5 to guide the chain. This A-frame carries a T-grooved bracket 6 which is formed with a removable cover 7 to guide the chain as it travels. This chain

is made up of a series of solid or substantially solid filler lug blocks 8 tied together on either side by substantially flat links 9, 9^a. These links 9, 9^a have flanges 10, 10 which project into the sides of the T slot to hold the chain in the track so that as the chain travels the blocks are dragged in this track, being loosely guided and held so that the links, particularly the lug block links which carry the lugs are free to move about within certain limits within the slot as they travel. Projecting upwardly from each of the filler or lug blocks in the chain is a hollow slotted lug and while the chain or tension part of each lug block or link is exactly the same as all the rest, it must be observed that this hollow lug or cutter box is different. For instance, as shown in Fig. 2, there are seven different lugs; one is located in the same plane as the link; three are located in inclined planes to one side and three in inclined planes to the other side. The chain is made up of alternate series of link blocks. These lugs or boxes themselves are each exactly the same as the other in so far as each block by itself is concerned but their relation with the link is different in that they are inclined on different angles and my invention has to do with the shape and arrangement of these lugs or boxes with respect to the link or lug blocks and the process whereby such arrangement is determined and effected.

Referring to Figs. 4, 5 and 6, it will be noted that the lug or box 11 is hollow and is made up of two parallel side walls tied together at the rear by the block 12 in which is screw-threaded a set screw 13. This set screw has its axis parallel with the axis of the link itself. The side walls are tied together also by the heavy boss or block 13^a having a toothed or serrated inner surface 14. The box, or rather the slot contained within it formed by the blocks and side walls is open on both sides, that is to say, above and below the heavy boss or block so that the boss or block forms with the side walls a kind of loop or stirrup in which the cutter bar 15 having its sides corrugated to engage the corrugations 14, is supported and held. This cutter has the sharpened cutting edge 16 upwardly and forwardly projecting above and in front of the chain itself. 17 is a wedge slidably mounted on the floor 18 of the slot or hollow por-

tion of the box and having a smooth inclined surface parallel with or substantially parallel with the axis of the cutter 14 when it is in working position so that when 5 it is thrust forward against the under side of the cutter it will clamp that cutter against the part 13^a and hold it in position. This wedge has on its rear side a boss or hump 20 which is engaged by the cup at the end 10 of the set screw. It moreover has a central aperture or slot 21 through which passes a pin 22 which pin is fixed at either end in the walls of the box or lug and while it leaves the wedge free to move back and 15 forth prevents its removal from the link. 23 is an aperture extending clear through the side walls of the lug adjacent the bottom of the groove or slot therein for the purpose of making it easier to clear the space behind 20 the wedge from any accumulation of dirt which might make it difficult to withdraw the wedge to release the cutter.

Referring now to Fig. 6, we note that the lower portion of the lug block is more or 25 less open or hollowed out as indicated in the section and it is apertured at either end to contain the sleeve 24 which projects inwardly from the link 9^a and a pin 25 which projects inwardly through the sleeve 24 30 from the link 9. This pin 25 is centrally countersunk as indicated at 27 so that the pin 25 may be upset or headed out flush with the outer surface of the link 9^a whereby the chain may be held together, without 35 any projecting parts which would interfere with its passage through the slot on the frame.

One important feature of my process of manufacturing and the product resulting 40 therefrom is that although the position of the cutting edge of each cutter in a group or series of seven is different from the position of any other, still the lug block, the cutter and wedge and the hollow or box 45 portion of the lug is exactly the same in every case, the only difference being that the position of the hollow box portion, wedge and cutter with respect to the lug block is different, and it will be necessary for me to 50 provide merely different connecting members or portions interposed between the hollow portion of the lug and the link block so that different positions of cutter and holding means may result. In considering 55 the layout of this chain or link block, I have regarded it as lying in a vertical plane and have treated the parts accordingly, so it will be understood that the chain itself in actual practice might assume any desired 60 position and be located in any desired plane.

Referring now to Fig. 5, it will be noted that the chain block or link and all the other parts are shown in section. *a* is an arbitrary point locating the cutting edge of the 65 central double ended bit, and this point is

exactly the same distance above the horizontal plane before each and every bit, no matter what its inclination. I have illustrated it as being $4\frac{7}{8}''$ above the chain, but it might be any arbitrarily selected distance. 70 The point *c* is located also on the axis of the cutting bit. It is arbitrarily selected, and is the same exactly in each and every link arrangement. The point *b* is another arbitrarily selected point. It is located in Fig. 75 5 in the same vertical plane in which the points *a*—*c* are located and is in every case in the same vertical plane in which the axis of the link itself is located, and it is the apex of the right-angled triangle in that 80 plane built upon the line *a*—*c* as its hypotenuse. In Fig. 5 it will be observed that the plane *a*—*b*—*c* is a vertical plane, and it is the axial plane of the link 8, the lug or box 11, the boss or block 13^a and the block 12, together with the cutting bit. In other words, all these parts are as shown in the plan view in Fig. 3. *d* is a point arbitrarily selected in the plane *a*—*b*—*c*, and it is always in that plane no matter what the inclination thereof. This point *d* is located on the line *e*—*d* which is the axial line of the set screw 13, and that set screw and its axial line is always in a horizontal plane *e*, always equally distant from the horizontal 95 plane in which the point *a* is located. The plane *g*—*h*—*j*—*k*, bounding as it does the rear side of the block 12, is always perpendicular to the line *e*—*d*, and is therefore always a vertical plane. In Fig. 5 it will be 100 observed that the line *f*—*d* coincides with the line *e*—*d*. In Figs. 7, 8, and 9 it does not, and the angle *f*—*d*—*e* is for each case the angle through which the lug or block 12 and set screw 13 must be revolved about 105 the point *d* in the plane *a*—*b*—*c*, in order that the line *e*—*d*, namely, the center line of the set screw may always be located in the same horizontal plane.

Having now laid out the arrangement 110 shown in Fig. 5 for the central cutting member, it becomes possible to lay out the remaining cutting members inclined as they are to the central member and changed in position as their supporting means are so 115 that their cutting edges shall all be in the same horizontal plane. For the purpose of illustrating the way in which this is done, I shall follow through a process of laying out the link block and cutter shown at the right 120 hand side of Fig. 2, and for the sake of convenience, in Fig. 4 I have omitted the two intermediate blocks between it and the central cutter. I have made a corresponding omission on the other side of the central 125 cutter.

The cutters act as picks and as they cut along they tear loose fragments of material. In order, however, to insure that the fragments cross the entire face of the cuts shall 130

- be dislodged it is desirable to group the cutters so that the summation of the cuts or dislodgment of each cutter in the group will produce the total width of the cut desired.
- 5 Of course the wider the cuts the more cutters and while at one place no one cutter is sure of cutting exactly its share still the summation throughout the entire length of the cut is perfectly satisfactory.
- 10 In laying out any of the remaining six after the first has been selected, we first decide upon a position for the point *a* which may be either in the same horizontal plane as the point *a* in Fig. 5 or in any other plane,
- 15 containing that point or in any other suitable position depending on the kind of cut, shape or contour of the surface to be thereby produced. The point *c* is, of course, always fixed, and this gives us the base line *a*—*c* upon which the center or axis of the cutter must rest. Referring, then to the Figs. 7, 8 and 9, we see that the line *a*—*c* is inclined from the vertical axial line in which it was in Fig. 5. I have shown it off-set 2 $\frac{1}{4}$ from the axial vertical plane *x*—*x*, and it is also 4 $\frac{5}{12}$ from the plane *y*—*y*. The line *a*—*c* being now fixed and since the points *c* and *b* are in all cases equidistant thus fixing the line *c* and *b*, it is possible to fix the point
- 20 *b* because that point must be kept in the vertical plane in which the point *c* is located and which passes through the center of the link block, and it therefore raises up sufficiently to bring it as it moves in that plane
- 25 to such a position that it is still the same distance from the points *c* and *a* and thus we have a right angle triangle whose hypotenuse is the line *a*—*c* whose base *b*—*c* is located in the plane *x*—*x*. The point *d* since
- 30 it is always in the plane *a*—*c*—*d* in the same position with respect to the points *a*—*c*—*b*, of course, moved upwardly and outwardly; the line *e*—*d* is always in a horizontal plane and thus it moves up enough to follow the
- 35 point *d*. It will be noted, however, that the line *e*—*d* is now inclined to the plane *x*—*x* and is a fixed line. With this line fixed it becomes easy to locate the plane *g*—*h*—*j*—*k* which is perpendicular to the line *e*—*d* and
- 40 which bounds one side of the block 12. The plane *a*—*c*—*b* fixes the axial plane in which the parts 13 $\frac{1}{2}$, 14, 11 and 12 are all fixed but these parts are rocked in two directions and as it is necessary to have them lie in this
- 45 plane and have them fixed and located by the line *a*—*c* it is evident that there is a gap between these parts and the link block itself taken as a unit and therefore all that is necessary is to fill in this gap, the necessary
- 50 straight lines and curves being perfectly obvious to anyone skilled in the art. The same process might be carried out for each and every link block, hug box, layout and the distance which the point of the cutter is removed from the central line is, of course,

easily determined and upon it depends all the other positions.

Under some circumstances it becomes desirable to have the bottom of the cut arc or curved shape instead of flat and in this case 70 a curve is drawn about the axis line *b*—*c* as shown in Fig. 5 of the proper curvature and the cutting points are set down sufficient to make them correspond with this curve in the usual manner. This, of course, 75 necessitates a slight change in the position but the process of locating the position is the same in every case, that is to say, in this case the plane in which the cutter points are located becomes a curved surface but it 80 is the bounding or fixed curved surface and the cutter points may be located within in exactly the same way as if it were a plane. It will be understood that the line *b*—*c* is substantially parallel with the bottom or path 85 of the wedge though it might be inclined slightly as I have shown by any suitable angle. This is of no particular consequence. Of course this inclination to the line *b*—*c* is the same for all positions of that line. The 90 line of the set screw changes with respect to that line since it remains in a horizontal plane whereas the line *b*—*c* remains in a vertical plane and so the two lines in the offset positions are not in parallelism since 95 the wedge conforms generally to the shape of the path and it is obvious that the inclination of the set screw to the back side of the wedge varies and for this purpose the boss 100 is provided. It will be observed that this 105 prevents binding or straining of the parts.

The use and operation of my invention are as follows:—Each link block is laid out in the manner previously specified so that the cutting edge or point of the cutter carried by it will lie in the proper position to do its share of the work. The cores and their parts are the same in each case and thus each link block may be cast in the usual manner without difficulty or complication. 110 The successive link blocks are then assembled into a chain serially so that when the cutters which are the same are held or locked into position the chain will be complete with each cutter point in its appropriate place. The chain is then mounted on the cutting machine and coal is cut by it in the usual manner. When it becomes necessary to remove any or all of the cutting blades owing to their having worn down or when it is desired to have them taken out, it is necessary only to release the set screw, move the wedge back until the corrugations on the cutter disengage from the corrugations on the block and the cutter can then be positioned by the operator and held by the hand of the operator in position until the wedge can be returned to lock the parts in position. The result of the above entitled process is therefore, that I obtain a 115 120 125 130

chain which is made up of a series of identical links carrying a series of identical boxes, the rigid connection between the blocks and links being variable to give the 5 different positions of the cutting teeth.

It will be noted that the hollow cutter lug or box on the link forms in effect a stirrup in which the cutter is held being wedged or clamped therein by the wedge which wedge 10 locks the cutter against the back wall of the stirrup to hold it in position.

I claim:

1. In a coal cutting chain a link, a stirrup carried thereby and projecting to one 15 side thereof, a cutter extending through the stirrup and means carried by the link for

clamping the cutter in position in the stirrup, said means comprising a lug projecting from the link behind the stirrup, a set 20 screw screw-threaded therein, a wedge slide- able along the wall of the link in opposition to the cutter adapted to be in operative en- gagement on the opposed side of the set screw.

2. In a coal cutting chain a link, a stirrup carried thereby and projecting to one 25 side thereof, a cutter extending through the stirrup and means carried by the link for clamping the cutter in position in the stir- 30 rup, said means comprising a lug projecting from the link behind the stirrup, a set screw screw-threaded therein, a wedge slide- able along the wall of the link in opposition to the cutter adapted to be in operative engage- 35 ment on the opposed side of the set screw and means for holding said wedge loosely in position in the stirrup in the end of the set screw cutter.

3. In a coal cutting chain a link, a hollow 40 pocket containing box projecting therefrom, one wall of said pocket being sharply in- clined to the axis of the chain, a cutter con- tained within said box in engagement with 45 said inclined wall, the end of the cutter pro- jecting beyond said wall, a wedge contained within said pocket in opposition to the cutter and a set screw screw-threaded in one

wall of the pocket engaging said wedge in opposition to the cutter.

4. In a coal cutting chain a link, a hollow 50 pocket containing box projecting therefrom, one wall of said pocket being sharply in- clined to the axis of the chain, a cutter con- tained within said box in engagement with 55 said inclined wall, the end of the cutter pro- jecting beyond said wall, a wedge contained within said pocket in opposition to the cutter and a set screw screw-threaded in one 60 wall of the pocket engaging said wedge in opposition to the cutter, means for loosely holding the wedge in the pocket in- dependent of its relation with the set screw and the cutter.

5. In a coal cutting chain a link, a hollow 65 pocket containing box projecting therefrom, one wall of said pocket being sharply in- clined to the axis of the chain, a cutter con- tained within said box in engagement with 70 said inclined wall, the end of the cutter pro- jecting beyond said wall, a wedge contained within said pocket in opposition to the cutter and a set screw screw-threaded in one 75 wall of the pocket engaging said wedge in opposition to the cutter, the side walls of the pocket being apertured behind the wedge.

6. In a coal cutting chain a link having a side wall slightly inclined to the axis of the chain, a stirrup carried by the link over- 80 lying said side wall, the cutter contained within said stirrup, a wedge slideable along the inclined wall in opposition to the cutter, a curved boss on the back of the wedge, a lug projecting from the link, a set screw screw-threaded in the lug having a cut end of substantially the same radius of curva- 85. ture as the boss and in engagement with the boss.

In testimony whereof, I affix my signature in the presence of two witnesses this sixth day of March, 1915.

RALPH J. TEETOR.
